(57) **CLAIM**

I claim the ornamental design for a broom housing assembly, as shown and described.

DESCRIPTION

FIG. 1 is a perspective view of a broom housing assembly;

FIG. 2 is a front view thereof;

FIG. 3 is a rear view thereof;

FIG. 4 is a side view thereof;

FIG. 5 is an opposite side view thereof;

FIG. 6 is a top plan view thereof; and,

FIG. 7 is a bottom view thereof.

The broken lines in the figures represent environment of the device and forms no part of the claimed design.

1 Claim, 4 Drawing Sheets
